UNITED STATES PATENT OFFICE.

JACOB H. WEBER, OF NEW YORK, N. Y.

DESIGN FOR A COMBINED PHONOGRAPH AND RADIO CABINET.

Application filed January 19, 1924. Serial No. 8,358. Term of patent 14 years.

To all whom it may concern:

Be it known that I, JACOB H. WEBER, a citizen of the United States, and a resident of the city of New York, in the borough of Manhattan and State of New York, have invented and produced a certain new, original, and ornamental Design for Combined Phonograph and Radio Cabinet, of which the following is a specification, refer-

ence being had to the accompanying drawing, forming part hereof, in which, the figure is a perspective view of my new design.

I claim:

The ornamental design for a combined phonograph and radio cabinet, as shown.

JACOB H. WEBER.
